UNITED STATES PATENT OFFICE.

WARNIE ALBERT FUSCH, OF DECATUR, ILLINOIS.

POWER-OPERATED RAZOR.

1,350,717.

Specification of Letters Patent. Patented Aug. 24, 1920.

Application filed October 31, 1919. Serial No. 334,743.

To all whom it may concern:

Be it known that I, **WARNIE ALBERT FUSCH**, a citizen of the United States, residing at Decatur, in the county of Macon 5 and State of Illinois, have invented new and useful Improvements in Power-Operated Razors, of which the following is a specification.

My invention relates to razors and has 10 particular reference to power operated razors.

Important objects of the invention are to provide a razor of the above mentioned character which will simplify and shorten 15 the usual process of shaving, which will dispense with the necessity of lathering the face, which will not require the usual keen cutting edge, which is self-sharpening to a considerable extent, which is highly safe in 20 operation, and which will cut the hairs in a proper and close manner without injury to the skin and will leave the skin in a healthy condition.

Other objects and advantages of the invention will be apparent during the course 25 of the following description.

In the accompanying drawings forming a part of this specification, and in which like numerals are employed to designate like 30 parts throughout the same,

Figure 1 is a side elevation of a razor embodying my invention,

Fig. 2 is a longitudinal section taken on line 2—2 of Fig. 1, parts being shown in 35 elevation,

Fig. 3 is a similar view taken on line 3—3 of Fig. 2,

Fig. 4 is a plan view of the device, and,

Fig. 5 is a perspective view of the rocker 40 cutter.

In the drawings, wherein for the purpose of illustration is shown a preferred embodiment of my invention, the numeral 10 designates the sides of a frame, carried by a base 45 11. This base is adapted for insertion between spaced sides 12 carried by the free end of a tubular support 13. The sides 10 are provided with spring catches 14, to engage within openings 15 formed in the tubular support 13. It is thus seen that the 50 frame of the razor is detachably secured to the free end of the tubular support. Extending centrally within the frame of the razor is a main pivot shaft 16, secured to 55 the sides 10 of the frame. This pivot shaft

extends through and supports the body portion 17 of the rocker cutter, provided with rearwardly extending operating arms 31. The body portion 17 is provided upon its forward side with one or more longitudinally inclined or helical blades 18, having oppositely arranged shearing edges 19 and 20. 60

The numeral 21 designates coacting blades, pivotally supported by shafts 22, secured to the sides 10. The forward portions 65 of the blades 21 are bent laterally and extend across the rocker cutter. The blades 21 are provided with straight shearing edges 23. These shearing edges permanently slidably contact with the blades 18, and the device is therefore self-sharpening, in whole or part. The blades 21 are permanently spaced, as shown in Fig. 4, providing an 70 opening 24, as the blade or blades 18 cannot enter this opening by virtue of its helical arrangement. In the blades 21 are holes 32 which have two duties, one to relieve any 75 heating of the blades, and the other to allow hairs cut to escape from the razor.

At their ends, the blades 21 carry rearwardly extending arms 25, apertured at 26, for loosely receiving pins 27, which in turn carry compressible coil springs 28, serving to engage the arms 25 and swing the blades 21 inwardly, whereby these blades have their 80 edges 23 held in yielding slidable contact with the blades 18.

The numeral 29 designates a rotatable operating shaft, suitably mounted within the tubular support 13 and driven by an electric motor or other suitable means. This rotatable shaft 29 is provided at its forward end with a cam head 30, fitting between the arms 31, and adapted to impart an oscillatory movement to the body portion 17 of 90 the rocker cutter. The vibratory movement of the body portion 17 of the rocker cutter, may be effected by a vibrating arm fitting between the arms 31, the operating power being supplied to the vibrating arm by an 95 electric coil incased in 13.

The operation of the device is as follows:

The rocker cutter is continuously oscillated and its shearing blade 18 reciprocated beneath and in slidable contact with the 105 shearing edges 23. The device is moved in proximity to the face, so that the blades 21 contact therewith, the hairs passing into the opening 24, and are cut or sheared by the coacting edges 19, 20 and 23. I have found 110

that it is not necessary to lather the face, prior to shaving, but this may be done if desired.

- 6 It is to be understood that the form of my invention herewith shown and described is to be taken as a preferred example of the same, and that various changes in the shape, size, method of applying power, and arrangement of parts may be resorted to 10 without departing from the spirit of my invention, or the scope of the subjoined claims.

Having thus described my invention, I claim:—

1. A razor of the character described, 15 comprising a frame, a shaft arranged centrally therein, a rocker cutter carried by the shaft and provided upon its forward side with helical blades having oppositely arranged shearing edges, rearwardly extending spaced arms carried by the rocker cutter, means engaging the arms to oscillate them, a pair of shafts secured to the frame and arranged upon opposite sides of the first named shaft, coacting blades pivoted upon the 20 last named shafts and having their forward ends extending across the rocker cutter and provided with spaced shearing edges, rearwardly extending apertured arms secured to the ends of the coacting blades, shafts held within the apertures, and compressible coil springs carried by the last named shafts and engaging the apertured arms.
- 25 2. A razor of the character described comprising a frame, a shaft arranged centrally therein, a rocker cutter carried by the shaft and provided upon its forward side with a helical blade having oppositely arranged shearing edges, rearwardly spaced

arms carried by the rocker cutter, means engaging the arms to oscillate them, a pair of shafts secured to the frame and arranged upon opposite sides of the first-named means, and coacting blades pivoted upon the 45 last-named shafts and having their forward ends extending across the rocker cutter and provided with spaced shearing edges slidably contacting with the helical blade.

3. A razor of the character described 50 comprising a frame, a shaft arranged centrally therein, a rocker cutter carried by the shaft and provided upon its forward side with a helical blade having oppositely arranged shearing edges, rearwardly spaced 55 arms carried by the rocker cutter, means engaging the arms to oscillate them, a pair of shafts secured to the frame and arranged upon opposite sides of the first-named means, coacting blades pivoted upon the 60 last-named shafts and having their forward ends extending across the rocker cutter and provided with spaced shearing edges slidably contacting with the helical blade, and yielding means to move the coacting blades 65 into contact with the shearing blade.

4. A razor of the character described comprising a support, a vibrating cutter member arranged therein and having a shearing blade, means to move the member, 70 coacting blades arranged upon the opposite sides of the member and having spaced shearing edges arranged in proximity to the shearing blade, rearwardly extending apertured arms secured to the ends of the 75 coacting blades, shafts held within the apertures, and compressible coil springs carried by the last-named shafts and engaging the apertured arms.

WARNIE ALBERT FUSCH.
